CHARLES R. MEITZLER, OF ROCHESTER, NEW YORK, ASSIGNOR OF ONE-HALF TO OSCAR H. PIEPER AND ONE-HALF TO ALPHONSE F. PIEPER, BOTH OF ROCHESTER, NEW YORK

SURGICAL INSTRUMENT

Application filed September 11, 1928. Serial No. 305,228.

The present invention relates to surgical instruments and more particularly to diagnostic lamps for dental and surgical use, one object being to provide an improved instrument of this class designed to protect the patient from the portions of the instrument which are disposed adjacent to and become heated by the lamp.

More particularly the invention has for its object to provide an instrument of the class described with a guard for protecting the mouth of the patient from the heat of the lamp and associated parts when the instrument is used within the mouth to inspect, or while operating upon the teeth, and where without the guard the lamp or adjacent parts which become heated thereby would be likely to burn the mouth or at least produce objectionable reactions on the part of the patient upon contacting of the heated parts with different portions of the mouth.

A further object of the invention is to provide in diagnostic lamps of the present type an improved guard for the purpose described in combination with a mirror supported by the guard and being adjustable toward and from the lamp through adjustment of the guard upon the instrument proper.

A further object of the invention is to provide in an instrument of the present type a simple, practical and economical form of construction, embodying unitary and readily detachable parts to facilitate cleansing or sterilizing of the same as well as interchangeability whereby a plurality of the units may be kept on hand and interchanged from time to time with one or more base units for supporting the detachable units.

To these and other ends the invention resides in certain improvements and combinations of parts, all as will be hereinafter more fully described, the novel features be-

ing pointed out in the claims at the end of the specification.

In the drawings:

Fig. 1 is an external view of an instrument embodying the invention;

Fig. 2 is a section taken longitudinally through the same;

Fig. 3 is a front view of the combined mirror and mouth guard shown attached to the outer end of the lamp casing;

Fig. 4 is a rear view of the same showing the guard and mirror detached from the casing;

Fig. 5 is a transverse section taken on the line 5—5 of Fig. 1, and

Fig. 6 is a transverse section taken on the line 6—6 of Fig. 1.

Similar reference numerals throughout the several views indicate the same parts.

Referring to the drawings, 10 represents a base unit adapted for connection with suitable supporting and conducting means not shown. The base unit preferably includes an upstanding tubular member 11, in the outer end of which is removably disposed a lamp unit including a socket 12 and a lamp 13 thereon, the socket having a bayonet joint connection with the tubular member 11 as shown in Fig. 2. The tubular member 11 constitutes one of the conducting or circuit elements for the lamp and has a reduced end portion 14 projecting through and from the base tube to form a contact portion for connecting the instrument with the circuit wires, not shown, said end portion being insulated from the base in any suitable manner. The other conducting or circuit element is preferably in the form of a metal post 15 mounted within and insulated from the tubular portion 14 of the lamp supporting member 11 and having suitable connections with the lamp socket.

A unitary casing is provided in the form of a tube 16 having a head 17 at one end into which is screwed the portion 18^a of the

base 10 projecting from a knurled portion 18 of the base as indicated in Fig. 2 whereby said units are made readily detachable. Supported on the outer end of the tubular casing is a cap or thimble 19 of light-transmitting material, preferably glass. The thimble has its inner end inserted within the outer end of the tubular casing and is secured therein by a suitable binder as indicated at 20 in Fig. 2, whereby a liquid tight joint is afforded between the thimble and tubular casing.

The guard for protecting the mouth of the patient from the heated parts surrounding or adjacent the lamp is preferably in the form of a sleeve which may be split for a portion or for all of its length as desired. The guard comprises a split inner end portion 21 slidably mounted upon and yieldably engaging the tube 16 to afford a clamping action by which the guard is held against accidental displacement. The guard proper embodies an enlarged end portion 22 spaced from and substantially surrounding the thimble 19 and the lamp therein and also a considerable portion of the outer end of the tube 16 as shown in Fig. 2. An air space or cooling chamber 23 is thus afforded between the guard and the thimble and the outer end of the tubular casing as well. The air is permitted to circulate within and through the space 23 by reason of the fact that the enlarged portion of the guard has an opening 24 extending its full length as best indicated in Fig. 4.

Heretofore the parts provided to extend around lamps of this class to prevent lateral projection of the light rays have been in contact with or in extremely close proximity to the lamps and consequently have become quickly heated and to such an extent as to often burn the patient's mouth when placed in contact therewith after the light has been turned on for a considerable length of time. Even when the parts do not become heated sufficiently to actually burn the patient, they heat up to such an extent as to produce an undesirable reaction on the part of the patient when contacting with any portion of the mouth. This condition is avoided with the present construction for the reason that the open air chamber 23 between the guard and the parts directly surrounding the lamp and lamp socket serves to insulate the guard from the heat of the lamp to such an extent that it will be kept comparatively cool under all conditions of service.

The guard also embodies means whereby when it is inserted upon the outer end of the tube 16 and moved inwardly thereon the operator will know when it has reached its normal position of adjustment. This means comprises one or more inwardly projecting parts 24, preferably struck inwardly from

the enlarged portion 22 of the guard and which are adapted to engage a suitable abutment or abutments on the tube 16 comprising in the present instance the outer end portion 25 of the tube, in contact with which is shown one of the projections 24 in Fig. 2.

The guard is provided with a pair of outwardly turned upper and lower portions 26 and 27 respectively, which are formed around a rod 28 and preferably soldered thereto at 29 as indicated in Figs. 5 and 6, so that the rod is firmly held by said portions. The upper end of the rod is provided with a casing 30 in which is disposed a reflecting mirror 31 inclined to the axis of the lamp for reflecting the light rays thereof transversely of said axis to the various parts to be examined.

When it is desired under certain conditions of usage to adjust the mirror relatively close to the lamp as indicated by the dotted line position of the latter in Fig. 1, it is only necessary to force the guard inwardly by exerting sufficient pressure thereon to cause the projecting parts 24 to override the abutment 25 on the tube 16, this being a comparatively easy operation since the split sleeve will yield sufficiently to permit it to expand the necessary amount for such a movement. The guard is also free to rotate upon the tube 16 and may be readily slipped on and off when it is desired to use the instrument without the guard. Furthermore, the guard and the mirror constitute a detachable unit which may be readily removed as such for the purpose of sterilizing from time to time. If preferred, a number of the guard and casing units may be kept on hand for interchangeable use with the lamp base unit 105 carrying the sleeve and socket parts 11 and 12 and the lamp 13, as shown in Fig. 2.

The lamp and lamp socket are also made detachable from the tubular member 11 by means of the bayonet joint connection shown in Fig. 2 whereby lamps of varying capacity may be used in making different kinds of examinations or whereby new lamps may be readily attached when required.

I claim as my invention:

1. A surgical instrument comprising a base, a lamp casing connected with the base, a support within the casing, a lamp within the casing upon the support, said lamp and support being detachable by a longitudinal movement through the inner end of the casing and a guard upon the casing having a portion spaced from and substantially surrounding that part of the casing in which the lamp is disposed whereby to afford an air space between said part and the guard, said spaced portion having an inwardly extending part arranged when the guard is inserted upon and moved inwardly on the sleeve to engage the end of the latter where-

by to check inward movement of said guard.

2. A surgical instrument comprising a base, a lamp tube connected therewith having a transparent outer end, a lamp supporting a transparent outer end, a lamp support 5 port detachably connected with the base and projecting within the tube for withdrawal therefrom, a lamp upon the support extending into said transparent outer end and removable with the support as a unit 10 through the inner end of the tube, and a guard mounted upon the outer end of the tube and having a portion spaced from and substantially surrounding the transparent end to afford an air space about the latter.
- 15 3. A surgical instrument comprising a base, a lamp casing detachably connected with the base, a lamp within the casing, a guard upon the casing having a split sleeve-like portion yieldably engaging and slidably 20 mounted upon the casing, said sleeve-like portion having an enlarged end spaced from and substantially surrounding that portion of the casing in which the lamp is disposed and means projecting inwardly from said 25 enlarged end and arranged to engage the casing to check the inward movement of the guard.

4. A surgical instrument comprising a base, a closed tube connected with the base 30 and having its outer end formed of transparent material, and a lamp support connected with the base and detachably extending within the tube and removable through the inner end thereof and removable from 35 the support as a unit and a lamp on the outer end of the support enclosed by said tube and a guard detachably secured upon the tube and having an enlarged portion substantially surrounding and in spaced relation to that portion of the tube surrounding 40 the lamp and provided with a lateral opening for the admission of air to the interior of the guard, said guard being detachable by an outward sliding movement 45 upon said end when the latter is in service position.

5. A surgical instrument comprising a base, a tubular casing carried thereby including a body portion and a transparent 50 outer end portion of a less diameter than the body portion, a lamp support within said body portion, a lamp upon the support projecting into said outer end portion and a guard slidably mounted upon the 55 body portion and having an enlarged outer end substantially surrounding the transparent portion in spaced relation thereto and having an inwardly projecting part for engagement with the outer end of the body 60 portion whereby to check inward movement of the guard.

6. A surgical instrument comprising a base, a lamp carried thereby, a member connected with and extending from the base 65 and having an abutment thereon, a split

sleeve slidably mounted on said member having a portion adapted to substantially surround the lamp in spaced relation thereto and provided with one or more inwardly extending parts arranged in one position of the sleeve to engage the abutment, the 70 yieldability of the sleeve being sufficient to permit said parts to override the abutment under a predetermined pressure upon the sleeve in one direction whereby the sleeve 75 may be adjusted longitudinally to a different position upon said member.
